US0D1025219S

(12) **United States Design Patent** (10) Patent No.: **US D1,025,219 S**
(45) Date of Patent: ** Apr. 30, 2024

(54) **MAGNETIC CHESS GAME**

(71) Applicant: **Yuxiang Chen**, Fu'an Fujian (CN)
(72) Inventor: **Yuxiang Chen**, Fu'an Fujian (CN)
(**) Term: **15 Years**
(21) Appl. No.: **29/921,856**
(22) Filed: **Dec. 19, 2023**
(51) LOC (14) Cl. **21-01**
(52) U.S. Cl. **USPC D21/341; D21/338**
(58) **Field of Classification Search**

USPC ..... (57) **CLAIM**

The ornamental design for a magnetic chess game, as shown and described.

DESCRIPTION

FIG. 1 is a perspective view of a magnetic chess game showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and,

FIG. 8 is a bottom plan view thereof.

1 Claim, 8 Drawing Sheets
